UNITED STATES PATENT OFFICE

2,073,527

CIRCUIT AND APPARATUS FOR OPERATING
ELECTRIC DISCHARGE LAMPS

Justin Peterson, Saugus, Mass., assignor to General Electric Company, a corporation of New York

Application February 28, 1935, Serial No. 8,632

3 Claims. (Cl. 176—124)

My invention relates to electric discharge lamps, and more particularly to a circuit and apparatus for operating them.

One object of my invention is to provide an improved starting apparatus for electric-discharge lamps when operated on series circuits.

Another object of my invention is to provide means for improving the operation of the lamp, particularly by reducing the outage time subsequent to a current interruption.

For a better understanding of my invention, together with other and further objects thereof, reference is had to the following description, taken in connection with the accompanying drawing, and its scope will be pointed out in the appended claims.

In the attached drawing, I illustrate diagrammatically my invention as applied to electric-discharge lamps of the type disclosed, for example, in U. S. Patent No. 1,948,261, and assigned to the assignee of the present invention. These lamps are commonly known as the high pressure mercury lamps, because during operation the mercury vapor pressure in the lamp rises 25 to a value which is substantially equal to atmospheric pressure. The single figure of the drawing illustrates a transformer 1 having its primary winding 2 connected into a constant current circuit. The secondary winding 3 of this 30 transformer is connected to electrodes 4 and 5 respectively of a discharge lamp 6 and is protected by an insulating film cutout 7.

In accordance with my invention the winding 8 of an ionizing transformer 9 is connected so 35 as to carry during operation the full load current between the electrodes 4, 5 and the winding 3. The secondary winding 10 of this transformer is connected across the electrodes 4 and 5 of the lamp having in series therewith the operating 40 coil 11 of a relay 12. This circuit may be traced from electrode 4 through conductors 13 and 14, winding 10, conductor 15, relay coil 11, conductor 16 and electrode 5. When thus connected the 45 potential of the secondary of the transformer 9 is materially higher than the potential of the secondary of the transformer 1.

The relay 12 is provided with a movable contact arm 17 which assumes a lower position when the coil 10 is deenergized or is energized insufficiently to lift its armature 18 to which the contact arm 17 is attached, and assumes an upper position when the coil 11 is fully energized. In the lower position contact arm 17 engages fixed contacts 19 and 20 and thereby closes a circuit 55 including the transformer windings 8 and 3 only.

This circuit may be traced from winding 3, conductor 21, contact 20, contact arm 17, contact 19, conductors 22 and 13, winding 8 and conductor 23 to winding 3. If the primary winding 2 is, therefore, energized, winding 3 energizes only 5 the primary winding 8 of the transformer 9. The secondary winding 10 being connected to electrodes 4 and 5 across the discharge lamp 6 produces an ionizing potential which gradually breaks down the resistance of the lamp and thereby builds up the current through the lamp. When this current flow reaches a predetermined value, the coil 11 moves its armature 18 and the contact arm 17 to the upper position to engage contact 24 while still engaging with the fixed 15 contact 20. In this position of the contact arm 17 the winding 3 is connected directly across the electrodes 4 and 5. The circuit may be traced from winding 3, conductor 21, contact 20, contact arm 17, contact 24 and conductor 16. 20

The connections between electrode 4 and winding 3 remain unchanged, and the winding 8 now carries the full lamp current. The secondary circuit of this transformer 9 also remains unchanged and the secondary winding 10 is connected across the electrodes 4 and 5 during operation. In the preferred arrangement of this apparatus this secondary potential is during starting considerably higher than the operating potential. In one of the lamps having an operating voltage of 155 to 160 volts the starting potential used is between 300 and 400 volts. The transformer is made of such high reactance that the current flow, when the winding 10 is connected across the winding 3, is only sufficient to maintain the relay contact arm 17 in its upper position and in engagement with the fixed contacts 20 and 24. For example, it may be of the order of 30 to 40 milliamperes. In this manner the ionizing action during operation is negligible, 40 but during fluctuations of current or temporary interruptions thereof the contact arm 17 is moved to its lower position to engage fixed contacts 19 and 20 and thereby disconnects the lamp from winding 3 and closes the circuit through winding 8. Upon a reenergization of the transformer the ionizing potential is therefore immediately available. 45

In the high pressure mercury lamps now available, the vapor pressure during normal operation of the lamp is approximately equal to atmospheric pressure. A momentary interruption of current, therefore, sufficient to interrupt the discharge in the lamp causes an interruption of operation until this pressure has 50 55

fallen to substantially initial pressure obtained at ambient temperature. It has heretofore been necessary to wait for the lamp to cool down to substantially ambient temperature before the 5 lamp could be started. With my arrangement as above described the time between interruption and restart has been considerably reduced since the cooling rate at the high operating temperature is high. The ionizing potential breaks 10 down the tube resistance at a pressure greatly in excess of that obtained at ambient temperature and therefore the time required to cool the tube through the latter part of the temperature difference, above ambient, is eliminated.

15 Another advantage of the above-described circuit is that a breaking down of the protective devices such as insulating film cut-out 7 is prevented. When current in the series circuit is interrupted only long enough to stop operations 20 of the lamp 6, the resistance of the lamp builds up immediately, and unless some by-pass is provided for the series transformer, a voltage will be built up across the terminals of the lamp of such magnitude that either a flash-over between 25 terminals occurs or the protective device is broken down, and, thereby, the lamp is shunted out of circuit. To put such lamps back into service, it requires the service of an attendant who would have to replace the protective device.

30 With my arrangement, the relay 11 operates when the current flow ceases, a predetermined constant load is thereby placed upon the series transformer, and, simultaneously, a predetermined ionizing voltage is placed across the lamp.

35 This ionizing voltage is, of course, of such magnitude that the most advantageous starting condition for the lamp is obtained.

What I claim as new and desire to secure by Letters Patent of the United States, is:

40 1. In combination, an electric discharge lamp, a transformer for supplying operating current

and a second transformer for supplying ionizing current to said lamp, and means responsive to the current supplied by said second transformer for effecting an energization of said lamp by said second transformer alone during the starting period of said lamp and for connecting said first transformer to said lamp during normal operation thereof.

2. In combination, an electric discharge lamp, a transformer for supplying operating current thereto and having a substantially constant current in its primary circuit, an ionizing transformer having a primary winding connected in series with said lamp during normal operation and a secondary winding permanently connected 15 in multiple with said lamp and a relay responsive to the current flow in said secondary winding for disconnecting said discharge lamp from said operating transformer and for simultaneously effecting an energization of said lamp by 20 said ionizing transformer during the starting period, and operable to connect said operating transformer to said lamp as soon as a predetermined current flows through said ionizing transformer winding.

3. In combination, an electric discharge lamp, an operating transformer, a second transformer having a primary winding connected in series with said lamp and a secondary winding connected in multiple with said lamp, and means responsive to current flow in said secondary winding arranged to connect said operating transformer across said primary winding when less than a predetermined current flows through said lamp and secondary winding, and to connect said operating transformer across said lamp and primary winding when such a predetermined current flows through said lamp and said secondary winding.

JUSTIN PETERSON. 40
